SOAKING PIT COVER HANDLING
APPARATUSEarl L. Raynor, Youngstown, Ohio, assignor to
Manning, Maxwell & Moore, Inc., Muskegon,
Mich., a corporation of New Jersey

Application December 1, 1938, Serial No. 243,364

5 Claims. (Cl. 212—4)

The invention relates to apparatus for lifting and displacing heavy objects and has particular reference to improved apparatus for removing and replacing the covers of metallurgical furnaces or soaking pits of the floor installed type.

A furnace of the above general character is usually closed by a removable cover adapted to fit over the mouth of the pit and to rest on the floor in which the pit is installed. Due to the high temperatures at which such furnaces are operated, the covers are generally constructed in the form of a metal frame lined with fire brick or other suitable refractory material. Such covers are so heavy and bulky that power actuated mechanism is required for handling them.

When a single cover handling device, such as a crane or trolley, is employed in handling the covers of a plurality of soaking pits, some means must be provided for temporarily connecting the lifting mechanism of the device with the various pit covers. The connecting mechanism heretofore available for this purpose has been relatively complicated and therefore expensive to install and difficult to maintain in satisfactory operating condition due to the extremely hard usage to which such apparatus is necessarily subjected.

With the foregoing in view, an important object of the invention is to overcome the above difficulties by providing an improved soaking pit cover trolley which can be quickly and easily connected with any one of a plurality of soaking pit covers, which is simple and rugged in construction, efficient and reliable in operation, and which is not likely to get out of order.

A more specific object is to provide improved means for establishing a temporary operative connection between the lifting mechanism of a soaking pit cover trolley and a pit cover so that the cover can be lifted from the pit and transported to one side thereof to give access to the pit and can thereafter be replaced over the pit and disconnected from the lifting mechanism.

Another object is to provide improved lifting mechanism particularly suitable for soaking pit cover handling apparatus.

Other objects and advantages of the invention will become apparent from the following detailed description of the preferred embodiment illustrated in the accompanying drawings, in which:

Figure 1 is a perspective view of a soaking pit cover trolley embodying the features of the invention.

Fig. 2 is a sectional view of the trolley showing details of the lifting mechanism.

Fig. 3 is an end elevation of the connecting means for establishing a temporary connection between the lifting mechanism and a pit cover.

Fig. 4 is a side elevation of the connecting means.

While the invention is susceptible of various modifications and alternative constructions, I have shown in the drawings and will herein describe in detail the preferred embodiment, but it is to be understood that I do not thereby intend to limit the invention to the specific form disclosed but intend to cover all modifications and alternative constructions falling within the spirit and scope of the invention as expressed in the appended claims.

Referring to Fig. 1 of the drawings, 5 indicates a soaking pit cover closing a pit furnace whose throat 6 opens in a masonry structure 7 constituting the floor of the furnace room. The cover 5, as herein shown, is fabricated from standard steel shapes comprising heavy channel side members 8 reenforced with channel columns 9 and I-beams 10. A refractory lining 11 of fire brick 20 protects the metal parts of the cover from the heat of the furnace. Flange plates 12, welded or otherwise secured to the side channels 8 so as to project below the lower edges of the channels, are adapted to fit into a recess 13 in the floor 25 1 encircling the mouth of the pit. The recess may be filled with sand or the like to seal the pit.

Rails 14 disposed in recesses 15 on opposite sides of the pit form a track for a trolley 20 30 which carries apparatus for lifting the pit cover to be described in detail hereinafter. Preferably, the rails 14 are extended along a row of pits so that the trolley 20 is enabled to serve all of the pits in the row, thus avoiding the necessity of providing separate cover handling apparatus for each pit. In any event, the rails 14 are extended far enough beyond the pit to permit the cover 5 to be moved laterally sufficiently to expose the throat 6 of the pit. 40

The trolley 20, as herein shown, comprises a generally rectangular frame consisting of end beams 21 and 22 connected by transverse box girders 23. Journaled on each end beam are a pair of flanged wheels 24 which support the trolley on the rails 14 so that it may be traversed from a position at one side of the pit to a position directly over the pit. 45

For traversing the trolley relative to the pit, one wheel of each pair is drivingly connected with a traverse shaft 25 which extends across the trolley and is journaled in suitable bearings 26 supported on cross beams 27 extending between the girders 23. The driving connection between the shaft and the flange wheels may be of any suitable character such as a chain and sprocket drive which, for purposes of safety, is enclosed by a suitable guard or housing 28. A motor 29 mounted on the wheel beam 21 is arranged to drive the shaft 25 through a speed reducer 29a. 60

Suitable limit switches may be interposed in the operating circuit of the motor in well known manner to automatically stop the trolley when it is spotted directly over a pit.

- 5 The trolley 20 is equipped with suitable lifting mechanism adapted to be temporarily connected with a pit cover for raising and lowering the cover vertically so that it may be transported to one side of the pit or replaced over the pit without 10 injuring the masonry structure around the pit throat. This reduces wear on the pit structure and cover, thus increasing their useful life and materially reducing maintenance expense. Moreover, it permits the use of a sand seal around 15 the cover so that heat losses are reduced to a minimum.

Referring now to Figs. 1 and 2, the lifting mechanism in its preferred form comprises a series of lifting elements herein shown as rockers 20 or bell cranks 31 arranged in pairs at opposite ends of the trolley. Each bell crank is pivotally supported on a cross plate 32 in the associated girder 23 by a pivot shaft 33. The bell cranks of each pair are arranged on a line extending 25 substantially parallel to the path of the trolley to facilitate connection of the lifting mechanism with the pit covers, as will appear presently.

Each of the bell cranks 31, as herein shown (Figs. 1 and 2), consists of a pair of triangular 30 steel plates 34 and 35 rigidly held in parallel spaced relation by a tubular spacing member or hub 36 welded to the respective plates. The pivot pin 33 extends through the hub which is fitted with suitable bearings 37 for the pin. 35 The bell cranks 31 are arranged to be rocked in unison by common power driven means. To this end, the bell cranks of each pair are operatively connected with an eccentric 41 keyed to a shaft 42 which extends across the frame of the 40 trolley intermediate the bell cranks forming the several pairs and is journaled in bearings 43 carried on the cross beams 27. The connection between each bell crank 31 and its associated eccentric is provided by a rigid arm 44 pivotally 45 connected at one end to the bell crank by a pivot pin 45 and having at its other end an eccentric strap 46 encircling the eccentric 41. Thus, while the operating arms of the bell crank of each pair are separate and independent parts, 50 they necessarily move together by reason of their connection with a common eccentric. Further, since both eccentrics are keyed to the same shaft 42, all of the bell cranks will be rocked in unison when the shaft is rotated. In order that the 55 bell cranks 31 may rock in the same direction, those located on one side of the frame have the arms 44 connected below the pivotal point of the bell crank, while those located on the other side of the frame have the arm connected above the 60 pivotal point, as shown in Fig. 2.

Power for driving the eccentric shaft 42 is supplied by a motor 47 through a speed reducer 47^a, drive shaft 48, and a suitable gear train enclosed in a housing 49, as shown in Fig. 1. A limit switch of any suitable construction may be operatively associated with the eccentric shaft 42 and adjusted to interrupt the operating circuit of the motor 47 when the eccentrics are turned into either of their dead center positions 70 so as to automatically stop the lifting mechanism in the proper position. In one dead center position, the bell cranks are rocked so as to lift the cover the maximum distance from the floor, while in the other position the cover is lowered 75 to the floor. By the use of eccentrics, the speed

reducer and driving gear train is relieved of substantially all strain while a cover is held in either raised or lowered position.

The lifting mechanism is arranged to be operatively connected with the pit cover 5 through the medium of novel connecting means including connecting members 51 (Figs. 2 and 3) carried by the respective lifting elements and arranged to cooperate with gripping members 52 secured to the pit cover. To facilitate such connection, the various members are constructed and arranged so that they may be brought into cooperative association or engaged by movement of the trolley 20 along its track. Disengagement of the members is effected by reverse movement of the trolley. 15 In the exemplary form of the trolley shown in the drawings, four connecting members 51 are provided, one for each bell crank 31. These members are suspended from the respective bell cranks so as to move vertically when the bell 20 cranks are rocked about their pivots.

As shown in Fig. 3, each connecting member 51 comprises a vertically disposed plate 53 having a reinforced flange plate 54 welded to its lower edge to form a rigid structure of inverted, generally T-shaped cross section. The connecting members associated with the bell cranks at the right side of the frame (as viewed in Fig. 2) are each formed with a relatively long upwardly projecting extension 55 adapted to be pivotally secured to the bell crank 31 by a pivot pin 55'. The connecting members for the left side of the frame differ from the members above described in that the extension designated as 55^a is substantially shorter than the extension 55. The connection 35 between this member and its associated bell crank is provided by a link 56 pivotally connected at opposite ends to the bell crank 31 and the extension 55^a by pivot pins 57 and 58, respectively.

The link connection for the left-hand connecting member of each pair is provided for the reason that the two connecting members are rigidly joined together by a lifting beam 61 which serves to hold the members in predetermined spaced relation and to maintain the flanges 54 of 45 both members in the same horizontal plane at all times. The lifting beam 61, as shown in Figs. 2 and 3, comprises a pair of angle bars 62 and 63 arranged back to back on opposite sides of the connecting member plates 53. The vertical webs 50 of the angle bars are welded or otherwise suitably secured to the plates and the bars are additionally connected together at intermediate points by cross members 64 welded to the horizontal webs 55 of the bars.

The gripping members 52, with which the connecting members 51 cooperate, are all of similar construction, and a description of one will therefore suffice. These members are mounted on the pit cover 5 in pairs spaced apart similar to and aligned with the pairs of connecting members carried by the trolley. In the particular embodiment illustrated, two pairs of gripping members corresponding to the two pairs of lifting elements are provided, although it will be understood that any number necessary to support the weight of the cover may be employed.

In the preferred form shown in Figs. 3 and 4, the gripping member 52 comprises a pair of inverted, generally U-shaped end plates 71 and 72. 70 The upstanding legs of the plates are rigidly connected by outer side plates 73 and inner side plates 74 which form rectangular box-like structures spaced on opposite sides of a central opening 75. Welded to the upper edges of the side 75

and end plates of the respective structures are a pair of top plates 76 which project partially over the opening 75 and thus form a T-slot for the reception of a connecting member 51. The spacing at the top plates 76 is slightly greater than the thickness of the lifting beam 61 so that the beam and connecting members 51 carried thereby may readily be inserted in the slot by endwise movement of the beam incident to traverse movement of the trolley relative to the pit. Further, the adjacent corners of the respective top plates are beveled as at 77 (Fig. 1) so that the connecting members may enter between the plates without danger of catching thereon. When the connecting members are engaged in the gripping members in the above manner, the flanges 54 project under the edges of the top plate 76 whereby to engage the plates and lift the gripping member and cover to which it is attached when the connecting member is raised by operation of the lifting mechanism.

The gripping members 52 may be secured to the cover 5 in any suitable manner so as to enable them to sustain the weight of the cover. As shown in Fig. 4, the members are arranged to straddle the channel columns 9 with the lower portions of the end plates 71 and 72 overlying the sides of the channel members. Pins 78 extending through the channels of the column and the depending ends of the members 71 and 72 hold the gripping member securely in place on the cover. To prevent accidental displacement, the pins 78 are drilled at each end for the reception of headed locking pins 79 carried by angle brackets 79a welded or otherwise secured to the end plates 71 and 72 of the gripping member. The locking pins may be pulled out to permit withdrawal of the supporting pins 75 when it is necessary to remove the gripping members for repairs.

It will be apparent from the foregoing that the invention provides a soaking pit cover handling apparatus of novel and improved construction. The apparatus includes a trolley carrying powerful and efficient lifting mechanism capable of being quickly and easily connected with any one of a plurality of soaking pit covers. The connecting mechanism, while efficient and reliable in operation, is of simple and rugged construction and not likely to get out of order or to require frequent attention. The work of the operator is greatly simplified since the connection of the lifting mechanism with a pit cover may be effected as an incident to the traverse movement of the trolley from a position of one side of the pit to a position directly over the pit. Disconnection of the lifting mechanism from the cover is likewise effected by the traverse movement of the trolley, the lifting mechanism being in its lowered position during such connecting and disconnecting movements.

I claim as my invention:

1. The combination with the lifting mechanism of a soaking pit trolley, of connecting means for operatively connecting the mechanism with a pit cover, said connecting means including a pair of vertically disposed plates, a flange plate rigid with the lower edge of each vertical plate and forming therewith an inverted generally T-shaped connecting member for cooperating with a gripping member on the pit cover, and a rigid beam secured to said vertical plates operative to hold the connecting members in predetermined spaced relation and to maintain the flange plates thereof in the same plane in all positions of the lifting mechanism.

2. Connecting means for operatively connecting the lifting mechanism of a soaking pit trolley with a pit cover, said connecting means comprising, in combination, a pair of vertically disposed plates, a flange plate rigid with the lower edge of each vertical plate and forming therewith an inverted generally T-shaped connecting member adapted to engage a cooperating gripping member on the pit cover, and a pair of elongated bars arranged on opposite sides of said vertical plates and rigidly secured thereto, said bars acting to hold the connecting members in predetermined spaced relation and to maintain the flange plates thereof in the same plane to facilitate engagement of the connecting members with the gripping members of the cover.

3. The combination with a lifting mechanism including a pair of pivoted rockers, of connecting means for operatively connecting the mechanism with a soaking pit cover, said connecting means comprising a pair of vertically disposed plates, a flange plate rigid with the lower edge of each vertical plate and forming therewith an inverted generally T-shaped connecting member adapted to engage with a cooperating part on a pit cover, a rigid bar connecting said vertical plates to hold the members in predetermined spaced relation, means connecting said members with the respective rockers so as to maintain the flange plates in a common horizontal plane when the rockers are operated including an extension on one of said vertical plates pivoted directly on one of the rockers, an extension on the other of said vertical plates, and a link pivoted at one end to said last mentioned extension and at the other end to the other of the rockers.

4. A gripping member attachable to the cover of a soaking pit and adapted for engagement with the T-shaped connecting member of a cover lifting mechanism, said gripping member comprising, in combination, a pair of generally U-shaped end plates, side plates connecting the legs of said end plates to form rigid box-like structures disposed on opposite sides of a central opening, and top plates rigidly secured to the upper edges of said side plates with their respective inner edges projecting over said opening to form an inverted T-slot for the reception of the connecting member.

5. A gripping member adapted for attachment to a cross member of a soaking pit cover comprising, in combination, a pair of generally U-shaped end plates, side plates connecting the legs of the end plates to form a pair of rigid box-like structures disposed on opposite sides of a central opening, said structures resting on the cross member of the pit cover with portions of said end plates depending on opposite sides of the cross member when the gripping member is assembled with a cover, top plates rigidly secured to the upper ends of said box-like structures with their respective inner edges projecting over the central opening to define a T-slot for the reception of a connecting member, and an elongated pin extending through the depending portions of said end plates and the cross member of the pit cover for detachably securing the gripping member to the cover.

EARL L. RAYSOR.
